AIR CONTROL FOR FURNACES

Earle W. Ballentine, Chicago, Ill., assignor, by
means assignments, to Fred E. Hummel, per-
manent trustee of Russell Electric Company,
Chicago, Ill., a corporation of Illinois

Application April 15, 1936, Serial No. 74,581

9 Claims. (CL 110—45)

This invention relates to air control for furnaces, and more particularly to means for controlling the volume of air positively fed to the combustion chamber of a furnace.

One feature of this invention is that it maintains the volume of air positively fed to the combustion chamber of a furnace substantially constant despite variations in the resistance of the furnace system to the flow of air therethrough; another feature of this invention is that it maintains the velocity of the air entering the fuel in the retort substantially constant; another feature of this invention is that it varies the volume of air fed to the combustion chamber in accordance with the rate of fuel feed thereto, whereby proper stoichiometric proportions of fuel and air are maintained; still another feature of this invention is that it regulates the volume of air delivered by a substantially constant speed centrifugal blower by means responsive to pressure changes between the blower and a valve or blast gate in the duct leading from the blower to the furnace; yet another feature of this invention is that it regulates the pressure at which the control means is operative, and consequently the volume of air delivered to the furnace, in accordance with the rate of fuel feed to the furnace; a further feature of this invention is that all motor means for the system are electrically operated; other features and advantages of this invention will be apparent from the following specification and the drawings, in which—

Fig. 1 is a side elevation, partly in section and partly diagrammatic, of a furnace equipped with this invention; Fig. 2 is a plan view, partly broken away, of the installation of Fig. 1; Fig. 3 is a sectional view of the retort along the line 3—3 of Fig. 1; Fig. 4 is a view along the line 4—4 of Fig. 3; Fig. 5 is a sectional view of the control means for the valve or blast gate motor; Fig. 6 is a view along the line 6—6 on Fig. 5; Fig. 7 is a vertical view, partly in section, of the motor means regulating the valve; Fig. 8 is a top plan view of this motor; Fig. 9 is a view along the line 9—9 of Fig. 7; Fig. 10 is an elevation, partly broken away, of the rheostat housing; and Fig. 11 is an end elevation, partly broken away, of the rheostat housing.

It is well known that variations in the relative quantities of fuel and air fed to the combustion chamber of a furnace system result in variations in combustion efficiency. A deficiency of air for a given quantity of fuel results in a failure to consume all of the fuel, with part thereof passing out of the flue with the gases of combustion

as soot and the like. Too great an excess of air for a given quantity of fuel results in a waste of heat in raising the temperature of the unused air and then allowing it to pass out of the stack, with the consequent loss of useful heat. Stoichiometric proportions have been worked out for practically all types of fuel, and it is recognized that these proportions must be closely followed for maximum efficiency. Regulation of the volume of air delivered to the combustion chamber of a furnace by a centrifugal blower operating at a substantially constant speed, for example, has many difficulties, principally because of the changes in the resistance of the furnace system to the flow of air therethrough. Changes in the direction of the wind, variations in the resistance of the flue and walls of the combustion chamber, variations in the compactness of the fuel bed where coal is used, and the like, all impose a varying resistance load on the blower. This varying resistance, of course, results in undesired variations in the volume of air passing through the combustion chamber.

This invention contemplates the introduction of another variable resistance in the system in the form of a valve or blast gate in the delivery duct and preferably a second variable at the point of entrance of the air into the body of fuel in the retort leading from the blower to the furnace. The blast gate, being adjustable, introduces a variable resistance in the system which is capable of adjustment, and by means of which variations in the other resistances may be compensated for to maintain a substantially constant over-all resistance to air flow through the furnace system. The blast gate is operated by a reversible shaped-pole electric motor which is automatically controlled by a switch responsive to pressure existing in the duct between the valve and the blower. Because of the rather definite pressure-volume relationship of the output of a substantially constant speed centrifugal blower, maintaining the pressure substantially constant behind the valve maintains the volume of air delivered to the combustion chamber of the furnace at the desired value.

In addition, means are provided for varying the maintained pressure and consequently the volume of air delivered to the combustion chamber, by and in accordance with changes in the rate of fuel feed to the combustion chamber. The control is interlocked with the speed regulating means for the fuel feed, for example, and an increase in fuel feed changes the pressure to which the valve motor control means is responsive.

Means are also provided for varying the effective size of the openings in the retort through which air enters the retort to support combustion of the fuel. The volume of air entering the retort varies with the rate of fuel feed, and it has been found advantageous to reduce the size of the openings as the volume of air is reduced, so that the stream of air entering the fuel always has sufficient turbulence and velocity to penetrate substantially to the center of the retort. This means is also interlocked with the speed regulating means for the fuel feed.

Referring more particularly to Fig. 1, 16 indicates a furnace having a retort 11, fuel feed conveyor means 12, air feed means 13, and boiler tubes 14. The other portions of the furnace system are not here illustrated, since they form no part of this invention. The fuel 15 is here shown as coal of the proper size, which coal is placed in the hopper 16 and carried into the combustion retort 11 by the conveyor 12 which is driven by a motor here indicated as 10, of a variable speed type. The speed at which the motor drives the conveyor 12 is controlled through a standard rheostat means in the housing 11, comprising a resistance element 12 and a movable contact arm 13 manually set by the handle 19. A centrifugal blower 20, driven at a substantially constant speed by an electric motor, is connected by a delivery duct 21 to the air inlet 13 of the furnace. Control of initiation and termination of feed to the furnace is by means of a standard limit switch 92 and room thermostat 93, connected to the system here illustrated through the pipe 17 and control duct 18.

An air control valve or blast gate 22 is mounted in the delivery duct 21 on a shaft 23, which shaft is connected through a gear reduction box 24 to a reversible electric motor 25. The motor has one side thereof connected to the line 26, and two wires 27 and 28 connecting it to contacts in the control means 29, which control means is responsive to the pressure in the duct 21 between the valve 22 and the blower 20, to which duct it is connected by the pipe 30. The pressure at which the contact 34 makes and breaks contact with the contacts 32 and 33 connected to the lines 27 and 28 is regulated by the setting of the plunger 31, which is controlled by the setting of the handle 19 which also controls the rate of fuel feed.

Referring more particularly to Figs. 5 and 6, the control means 29 will be described in more detail. The control means has therein a pair of contact points 32 and 33 connected to the lines 27 and 28, and adapted to be contacted by the point 34 carried by the resilient member 35, which member is preferably of spring metal. The member 35 is mounted upon, although electrically insulated from, the movable member 36 rockably mounted on the pivot 37. The movable member 36 is contacted by the saddle 38 mounted on the rod 39, which rod is connected to the diaphragm 40 in the diaphragm chamber 41. It will be noted that the pipe 30 opens into the chamber on one side of the diaphragm 40, and the position of the diaphragm is thus a result of two opposed forces, one exerted by the air pressure in the duct between the valve and the blower, and the other exerted by the spring 42. The compression or pressure of the spring 42 is regulated by the plunger 31, and is a function of the position of the arm 43 carried by the shaft carrying the manual handle 19 which regulates the rate of fuel feed to the furnace. The system is so arranged that the movement of the manual con-

trol handle 19 to a setting which reduces the rate of fuel feed to the furnace results, through the arm 43 and the plunger 31, in increasing the pressure in the spring 42. The contact point 34 then closes with contact 33, completing a circuit which rotates the motor 25 in a direction closing the valve or blast gate 22. The valve is closed until the pressure between it and the blower rises to a point sufficient to slightly overcome the spring pressure, at which time the contact points 32 and 33 open. Increase in pressure in the delivery duct is accompanied by a decrease in the volume of the air delivered to the furnace, the control system being so arranged that the decrease in air maintains the proper stoichiometric proportions with the decreased rate of fuel feed. Current is supplied to the strip 35 from the line or source of electric current by the wire 44, through the flexible pigtail 34. The strip 35 is free to assume a position dependent upon the pressure upon the diaphragm 40, and when the pressure is at the desired point the contact 34 floats between the two contacts 32 and 33; it is only when the pressure is above or below the desired value for any given fuel feed rate that the contacts close to change the position of the valve and bring the pressure to the desired value. A small permanent magnet 45 is mounted just behind the contact 32, and the relation between the flexible member 35 and the pull of the permanent magnet 45 on the contact point 34 results in a snap action of the switch.

Referring more particularly to Figs. 7, 8 and 9, the electric motor and reducing gear system controlling the position of the valve 22 will now be described in more detail.

The motor 25 has a frame 46, which frame, in addition to supporting the various parts of the motor, serves as a path or core for the flux produced by the coils 47 and 48. These coils have 40 pole pieces 49 and 50 mounted therein, which pole pieces are of the shaded type adjacent the disk 51 carried by the shaft 52, having portions thereof surrounded by the shading coils 74 and 75. The position of the shaded portions of the pole pieces 49 and 50 with respect to the disk 51 is such that when coil 47 is operative and coil 48 inoperative the disk revolves in one direction, and when coil 48 is rendered operative and coil 47 inoperative through the action of the control switch 29 the disk 51 revolves in the opposite direction. The shaft 52 is connected through a train of reducing gears to the shaft 23, which carries the valve or blast gate 22. The position of the valve is thus controlled by the reversible electric motor, controlled in turn by the switch 29. Since the position of the contacts in the switch 29 is a result of two factors, the speed setting of the fuel feed and the air pressure in the duct 21, the setting of the valve 22, and consequently the volume of air passing through the combustion chamber of the furnace system, is thus a function of these two factors.

The capacity of the blower 20 is chosen to be sufficient for the highest rate of fuel feed of the system and the highest resistances to air flow expected to be encountered in the furnace system. Changes in the setting of the fuel feed means effects a change in the pressure to which the control switch 29 is responsive, and consequently 70 introduces another resistance in the system, through change in the position of the valve 22, such that the new volume of air delivered maintains the proper stoichiometric proportion with the new rate of fuel feed. Constant changes in 75

the variations of pressure in the furnace system resulting from changes in the fire bed, changes in wind direction, and the like, are compensated for by changes in the position of the valve 22 so 5 that the over-all resistance of the system is constant, at such a value as maintains the proper volume of air flow.

Referring more particularly to Figs. 1-4, it will be seen that the combustion chamber of the 10 furnace 10 is provided with a retort 11 adapted to support combustion by underfed stoking of its fuel content 61. The retort 11 has openings 62 through the sides thereof, through which openings the air delivered by the centrifugal blower 20 through the duct 21 passes on its way to the combustion chamber of the furnace 10. The retort has around it a sleeve 63, here shown as a light gauge sheet of metal, which sleeve is so mounted as to be able to rotate through a limited 15 arc about its axis, which is also the axis of the retort. The sleeve is provided with openings 64 which are adapted to register with the openings 62 in the retort, either wholly or in part, in accordance with the position of the sleeve. The 20 sleeve has attached thereto on one side thereof a lug 65 to which is connected a rod 66 projecting outside of the combustion chamber of the furnace and connected at its other end to a bell crank 67 mounted on the outside of the furnace. 25 The rod 66, where it passes through the wall of the combustion chamber, is provided with a substantially air-tight packing of any well-known type, in order to prevent leakage of the air being delivered to the retort by the blower 20. The 30 other end of the bell crank 67 is connected by the rod 68 to the control lever 19 which regulates the rate of fuel feed to the retort, and also, through the plunger 31, the volume of air delivered to the combustion chamber of the furnace. 35

It is, of course, necessary to make the openings 62 in the retort and the corresponding openings 64 in the sleeve large enough to pass, without substantial resistance, the volume of air necessary for proper stoichiometric proportions at the highest rate of fuel feed of which the stoker system is capable. When a large volume of air is being delivered to these openings, the velocity of the air therethrough and its turbulence after it has passed therethrough is sufficient to insure penetration practically to the center of the fuel conduit of the retort. Heretofore, no provisions have been made in the art for decreasing the effective size of these openings when the fuel and air feed rate was decreased, and poor combustion in the center of the fuel bed resulted. It has been found that if the openings remain of the same size while the volume of air delivered is cut to one-fourth, for instance, the air has not sufficient velocity to penetrate more than a few inches into the fuel content of the retort, and then passes upwardly into the combustion chamber, thus leaving a central mass of fuel to which sufficient air is not being delivered to properly 50 support combustion.

Applicant has discovered that if the effective size or area of the openings is reduced, as by his supplemental sleeve, the velocity of the air entering the retort may be maintained high enough to 55 insure proper penetration and distribution through the fuel content even when a smaller volume of air is being delivered to the combustion chamber to maintain proper stoichiometric proportions with a smaller quantity of fuel being fed thereto. It will be thus seen that in the sys-

tem disclosed herein the control lever 19 not only controls the rate of fuel feed to the furnace, but also controls the volume of air delivered to the combustion chamber and the penetration of that air into the fuel content of the retort. The controls are, of course, so set that the volume of air delivered to the combustion chamber at any given stoker rate setting is substantially that proportion found to provide most efficient combustion. 5

While I have shown and described certain embodiments of my invention, it is to be understood that it is capable of many modifications. Changes, therefore, in the construction and arrangement may be made without departing from the spirit and scope of the invention as disclosed 10 in the appended claims, in which it is my intention to claim all novelty inherent in my invention as broadly as possible in view of the prior art. 15

What I regard as new and desire to secure by 20 Letters Patent, is:

1. Apparatus of the character described, including: a furnace; a substantially constant speed centrifugal blower; a duct for delivering the air from said blower to said furnace; a valve in said duct; means for varying the position of said valve by and in accordance with the pressure in said duct between said valve and said blower; and means for varying the position of said valve by and in accordance with the rate of fuel feed 30 to said furnace.

2. Apparatus of the character described including: a furnace; a substantially constant speed centrifugal blower; a duct for delivering the air from said blower to said furnace; a valve 35 in said duct; motor means for varying the position of said valve; control means for said motor, said control means being responsive to variations in air pressure in the duct between said valve and said blower; and means for varying 40 the pressure level to which said control means is responsive by and in accordance with the rate of fuel feed to said furnace.

3. Apparatus of the character described, including: a furnace; variable fuel feed means; 45 a substantially constant speed centrifugal blower; a duct for delivering the air from said blower to said furnace; a valve in said delivery duct; motor means for varying the position of said valve; a pressure responsive switch for controlling said motor, said switch being responsive to the pressure existing in the delivery duct between the valve and the blower; and interconnecting means between said switch means and said variable fuel feed means whereby the volume of air delivered to said furnace is proportional 50 to the amount of fuel fed thereto.

4. Apparatus of the character described, including: a furnace; fuel feeding means therefor; means controlling the rate of fuel feed; a 60 substantially constant speed centrifugal blower; a duct for delivering the air from said blower to said furnace; a valve in said duct; a reversible electric motor connected to said valve; a control switch for said motor, said switch having a 65 diaphragm and a compression means therein; means whereby the compression in said compression means is regulated by and in accordance with the rate of fuel feed; and means so constructed and arranged that the pressure in 70 said duct between said valve and said blower is maintained substantially proportional to the compression in said compression means, whereby the volume of air delivered to the combustion chamber of said furnace is maintained substan- 75

tially constant at any set rate of fuel feed despite variations in the resistance to the flow of air through said furnace.

5. Apparatus of the character described, including: a furnace having a combustion chamber; a retort in said chamber, said retort having openings therethrough for the admission of air thereto; means for delivering a volume of air to said retort, said volume being variable; 10 and means for varying the effective size of said openings substantially in accordance with the volume of air delivered to said retort.

6. Apparatus of the character described, including: a furnace having a combustion chamber; a retort in said chamber, said retort having openings therethrough for the admission of air thereto; means for feeding fuel to said retort; means for varying the rate of said fuel feed; means for delivering air to said retort; 20 means for varying the volume of air delivered thereto by and in accordance with the rate of fuel feed; and means for varying the effective size of said openings substantially in accordance with the volume of air delivered to said combustion chamber, whereby proper distribution of 25 said air through the fuel content of said retort is maintained.

7. Apparatus of the character described, including: a furnace having a combustion chamber; a circular retort in said chamber, said retort having openings through the walls thereof communicating with an air chamber for the admission of air to said retort; a sleeve surrounding said retort and rotatable axially with respect thereto, said sleeve having openings therethrough adapted to register with those through the wall 30 of the retort; means for feeding fuel to said

retort; means for varying the rate of said fuel feed; means for delivering air to said air chamber, said air passing through the openings in said retort wall; means for varying the volume of air delivered to said chamber in accordance 5 with the rate of fuel feed; and means for rotating said sleeve about its axis to vary the effective size of the openings through which said air passes.

8. Apparatus of the character claimed in claim 10 7, wherein the means for rotating said sleeve is operated by and in accordance with the rate of fuel feed to said retort.

9. Apparatus of the character described, including: a furnace having a combustion chamber; a circular retort in said chamber having openings through the wall thereof; a sleeve around said retort having openings therethrough adapted to register with said first-mentioned openings to afford communication thereof with 20 an air chamber therearound; means for feeding fuel to said retort; a substantially constant speed centrifugal blower; a duct for delivering the air from said blower to said air chamber; said air may pass through the openings in said sleeve 25 and said retort wall to said combustion chamber; a valve in said duct; motor means for varying the position of said valve; control means for said motor, said control means being responsive to air pressure in the duct between said valve and 30 said blower; means for varying the pressure to which said control means is responsive by and in accordance with the rate of fuel feed to said furnace; and means for varying the registry of said openings by and in accordance with the 35 rate of fuel feed to said furnace.

EARLE W. BALLENTINE.
